ATTORNEY

UNITED STATES PATENT OFFICE.

ANDREW SEKULO, OF WASHINGTON, PENNSYLVANIA.

CURTAIN-FIXTURE.

1,087,611.

Specification of Letters Patent.

Patented Feb. 17, 1914.

Application filed May 1, 1913. Serial No. 764,862.

To all whom it may concern:

Be it known that I, ANDREW SEKULO, a subject of the Emperor of Austria-Hungary, residing at Washington, in the county of Washington and State of Pennsylvania, have invented certain new and useful Improvements in Curtain-Fixtures, of which the following is a specification, reference being had therein to, the accompanying drawing.

This invention relates to curtain fixtures, and the primary object of my invention is to furnish a window, door or alcove frame with a single bracket for adjustably supporting a curtain pole to which one or more curtains can be easily and quickly attached and suitably draped to present a neat and attractive appearance in connection with the frame.

20 A further object of this invention is to provide a simple, durable and inexpensive bracket that can be attached to a frame or other support for adjustably and pivotally holding an end of a curtain pole, the pole being constructed whereby curtains or draperies can be attached to the same without resorting to the use of rings or pins that have a tendency to injure a curtain.

With the above and other objects in view 30 the invention resides in the novel construction, combination and arrangement of parts to be hereinafter specifically described and then claimed.

Reference will now be had to the drawing, 35 wherein,

Figure 1 is a front elevation of a curtain fixture in accordance with this invention, Fig. 2 is an enlarged perspective view of the same, partly broken away and partly in section, and Fig. 3 is a vertical sectional view of a portion of the fixture.

A curtain fixture in accordance with this invention comprises an upright 1 rectangular in cross section and provided with a longitudinal bore 2. In communication with said bore is a longitudinal slot 3 that is formed in the front side of the upright, said slot extending from the upper end thereof to a point in proximity to the lower end. 45 The upright 1 is provided with side extensions 4 adapted to be connected to a frame 5 or other support by set screws 6. Slidably

in the bore 2 of the upright is a rod 7 having the lower end thereof notched, as at 8 whereby said rod can be easily shifted in the bore. To hold the rod in adjusted position the lower end of the upright has a set screw 9, which can be adjusted to engage the rod and lock the same relatively to the upright. Attached to the upper end of the rod 7 is the tongue 10 of a bracket 11 that rides against the front side of the upright. The outer end of the bracket has a vertical opening 12 to receive the tongue 13 of a supporting block 14. Pivotedly connected to the block 14 by a screw 15 or other pivotal means is a horizontal rod body 16 that is channel-shaped in cross section. Arranged within the rod body 16 is a flat rod 17 and by placing a curtain in engagement with said rod and forcing the rod into the body 16 the curtain is firmly held relatively to the rod body. One or more curtains can be supported by the flat rod 17 and when it is desired to clean the frame or support 5 the rod body can be swung outwardly relatively to the frame to permit of easy access being had thereto.

One embodiment of the invention has been illustrated in the accompanying drawing, 80 but it is to be understood that the structural elements are susceptible to such variations and modifications as fall within the scope of the appended claim.

What I claim is:—

85 A curtain fixture comprising an upright adapted to be secured to the side of a frame, said upright having a longitudinal slot and bore formed therein, a rod adjustably mounted in the bore of said upright, a bracket having a tongue extending through the slot of said upright and connected to said rod, a block connected to the outer end of said bracket, a channel-shaped rod body having an end thereof pivotally connected 90 to said block, and a flat rod adapted to fit in said body.

In testimony whereof I affix my signature in the presence of two witnesses.

ANDREW SEKULO.
